UNITED STATES PATENT OFFICE.

ROBERT J. MURRAY, OF PHILADELPHIA, PENNSYLVANIA, ASSIGNOR TO FRANCIS A. BRUNER, INC., OF PHILADELPHIA, PENNSYLVANIA, A CORPORATION OF NEW JERSEY.

DESIGN FOR A VALANCE FOR WINDOW DRAPERIES.

Application filed October 11, 1927. Serial No. 23,718. Term of patent 3½ years.

To all whom it may concern:

Be it known that I, ROBERT J. MURRAY, a citizen of the United States, residing in Philadelphia, in the county of Philadelphia and State of Pennsylvania, have invented a new, original, and ornamental Design for a Valance for Window Draperies, of which the following is a specification, reference being had to the accompanying drawing, forming part hereof.

The figure is a face view of a portion of

the horizontal width of a valance for window draperies, the design being repeated throughout the width of the valance.

I claim:

The ornamental design for a valance for window draperies, substantially as shown and described.

In testimony whereof I have hereunto signed my name this 6th day of October A. D., 1927.

ROBERT J. MURRAY.
